No. 729,631.

PATENTED JUNE 2, 1903.

J. A. MILLER.

COIN CONTROLLED MIRROR RECEPTACLE.

APPLICATION FILED MAR. 3, 1902

NO MODEL.

UNITED STATES PATENT OFFICE.

JAMES A. MILLER, OF SAN FRANCISCO, CALIFORNIA.

COIN-CONTROLLED MIRROR-RECEPTACLE.

SPECIFICATION forming part of Letters Patent No. 729,631, dated June 2, 1903.

Application filed March 3, 1902. Serial No. 96,417. (No model.)

To all whom it may concern:

Be it known that I, JAMES A. MILLER, a citizen of the United States, residing at San Francisco, in the county of San Francisco and State 5 of California, have invented certain new and useful Improvements in Coin-Controlled Mirror-Receptacles, of which the following is a specification.

My invention relates to improvements in 10 coin-controlled mirror-receptacles, the object of my invention being to provide a device of this character which can be attached to the back of a chair in a theater or other public place and which by the insertion of a suitable 15 coin can be opened to permit the mirror to be withdrawn to assist in adjusting the hair or dress of the person seated in the chair immediately behind the receptacle or for other uses.

My invention therefore resides in the novel 20 construction, combination, and arrangement of parts for the above ends hereinafter fully specified, and particularly pointed out in the claims.

In the accompanying drawings, Figure 1 is 25 a perspective view of chairs provided with my improved mirror-receptacle. Fig. 2 is a perspective view from the front of said receptacle, on an enlarged scale, the mirror being withdrawn therein. Fig. 3 is a similar view 30 showing the mirror exposed. Fig. 4 is a view from the rear showing the mechanism for controlling the operation of the device by means of a coin. Fig. 5 is a broken view of the rear side of the mirror-frame. Fig. 6 is 35 an enlarged vertical section on the line A A of Fig. 4. Fig. 7 is an enlarged horizontal section on the line B B of Fig. 4.

Referring to the drawings, 1 represents a suitable box having narrow ends 2, a front 3, 40 a bottom 4, and a top 5. The ends of the box extend above the top thereof, and in the inner surfaces of said ends are formed grooves 7, which extend vertically to a point near the top thereof, whence they extend horizontally and forwardly, as shown at 8. In said grooves slide studs 9, which extend from the lower edge of a mirror-frame 10, which frame lies in the back of the box against the back of a chair 11, to which back the box is attached by means of screws 12. The mirror-frame can be drawn upward out of the space between the box and the back of the chair by

means of a finger-piece 13, the studs 9 then sliding in the grooves 7, and when so drawn upward and outward it can rest upon the front 55 edge 14 of the top of the back, the studs 9 then resting in the horizontal portions 8 of the grooves. The angle of inclination of said mirror can be adjusted by means of notches 15, formed in the upper sides of said horizontal grooves 8. Thus if it be desired to lower the front edge of the mirror the studs 9 will rest in the foremost notches, whereas if it is desired to give the mirror a smaller inclination to the horizontal the studs will rest in 60 the notches at the rear. When the mirror-frame is pushed back into place, so that the studs rest in the bottom of the grooves 7, said frame will be normally held from withdrawal by means of a locking-bar 16, which 70 slides in a suitable guideway 17, cast or otherwise formed in the rear surface of the front 3 of the box, the end of said bar being bent, as shown at 18, and said bent end extending when the mirror-frame is down over the top 75 of a wedge-shaped projection 19, cast or otherwise formed on the back of said frame. 20 is a spring which normally moves said locking-bar inward, so that said bent end extends over the top of said projection. 80

21 is an opening in the top of the box for the insertion of a coin, said coin when so inserted rolling down a chute 22 and falling into a contracted neck against a head 23, formed on the end of the locking-bar and held 85 up thereby. 24 represents a spring-resisted pusher which slides in a vertical groove 25 and can be pushed down upon the edge of the coin when in such position, the effect being to move said locking-bar outward and to permit the coin to drop past the narrow neck into the bottom of the box. The outward movement of said locking-bar moves its end from above the top of the projection 19 and releases the mirror-frame. The bottom of 90 the mirror-frame rests upon a spring 26, secured upon the bottom of the box, so that upon its being released said spring immediately raises said mirror-frame a short distance, when it can be further withdrawn by 100 means of the finger-piece 13. After the departure of the audience the attendant of the theater or other person having charge of these devices will push down the mirror into place.

As the mirror-frame descends the end of the locking-bar will slide against the inclined side 27 of the wedge-shaped projection and will thereby be moved outward until it reaches 5 the top of the projection 19, when it will immediately move over the same under the action of the spring 20.

28 represents a partition dividing the department for the coin from the space for the 10 mirror, and 29 represents a false bottom which slides in a suitable guideway 30 in the bottom of the box over an elongated opening therein and secured by means of a staple 31 and lock 32. By withdrawing the slide the 15 coins will be allowed to fall into any suitable receptacle.

I claim—

1. In combination, a receptacle having narrow ends extending above the top of the 20 receptacle and having grooves in the inner sides of said ends, said grooves extending

vertically to a point near the top thereof and then extending horizontally, and a mirror having studs sliding in said grooves, substantially as described.

2. In combination, a box having narrow ends extending above the top of the box, and having grooves on the inner surface of said ends, said grooves extending vertically to a point near the top thereof, and then horizontally, said horizontal portions of the grooves being formed with a series of notches, and a mirror having studs sliding in said grooves, substantially as described.

In witness whereof I have hereunto set my 35 hand in the presence of two subscribing witnesses.

J. A. MILLER.

Witnesses:
